Atty.

UNITED STATES PATENT OFFICE

ALFRED JOHNSON, OF CHICAGO, ILLINOIS

SHOE CONSTRUCTION

Application filed March 31, 1930. Serial No. 440,191.

This invention relates to shoe construction in general and particularly to shoe construction which is applicable to ice skates. More specifically, the invention relates to means for reinforcing the sole of an ice skate shoe.

Shoes used in ice skating and particularly skating shoes which have skates permanently attached thereto, become worn at the outside of the sole particularly at a point opposite the ball of the skater's foot. The sole becomes worn, scuffed, and crushed due to the edge of the sole engaging the ice in skating and particularly when the skater turns corners. Sometimes the shoe sole is so badly worn that the connecting members between the shoe sole and the skate become torn loose and even the upper of the shoe becomes scuffed and worn due to the wearing away of that part of the sole which comes in contact with the ice. The present invention overcomes the disadvantages inherent to conventional types of skate shoes and its primary object is to provide new and novel means for reinforcing the shoe sole to prevent wear along the edge of the sole.

Another object is to provide a metal reinforcement which extends around the edge of the shoe sole and is rigidly fastened to the upper bottom sides of the sole along the edge thereof.

A further object is to provide a reinforcing member for ice skate shoes which prevents the wearing of the sole due to the edge of the sole coming in contact with the ice and which may be applied to the sole before the upper is attached thereto, after the upper is fastened to the sole and before the shoe is fastened to the skate, or after the skate is attached to the shoe.

Numerous other objects and advantages will be apparent throughout the progress of the following specification.

The invention comprises in general a substantially U-shaped metal clip which is adapted to extend around the outer edge of the sole of an ice skating shoe and which is fastened to the sole in a rigid manner. The clip is preferably made of light sheet metal and is made U-shaped to provide a recess into which the protruding edge of the shoe sole is received.

Means are provided for pressing the metal along the edge of the clip into the protruding sole edge at the top and the bottom thereof. This fastening may be accomplished by inserting the protruding sole edge into the clip and then passing the edge through a device termed a "rule", whereby, indentations or cleats are provided for pressing a part of the metal into the shoe sole. The fastening may comprise indentations pressed into the metal for holding the clip securely to the protruding edge of the shoe sole, or the fastening may be accomplished by impinging the edges or turning them inwardly into the sole as will more fully hereinafter appear.

The accompanying drawings illustrate a selected embodiment of the invention and the views therein are as follows:

Fig. 1 is an elevation of a skate shoe having the invention applied thereto.

Fig. 2 is a transverse sectional view on the line 2—2 of Fig. 1.

Fig. 3 is a detail perspective view of one form of the metal clip.

Figs. 3A, 3B, and 3C are detail views showing the manner in which the clip may be applied to a shoe sole.

Fig. 4 is a detail perspective view of a slightly different form of clip.

Fig. 5 is a detail sectional view showing the manner in which the clip shown in Fig. 4 is applied to the shoe sole.

Fig. 6 is a detail perspective view of a shoe sole having the reinforcing member or clip extending completely around the periphery of the sole.

Referring to the drawings, 10 designates a skating shoe having the usual shoe sole 11 fastened thereto in the usual conventional manner. A skate 12 having the shoe engaging surfaces 13 and 14 is rigidly fastened to the shoe sole by means of rivets or other fastening means 15. The shoe sole extends beyond the outer edge of the shoe to provide a projection 16.

A sheet metal clip 17 is preferably made U-shaped and has an outer portion 18 and a pair of parallel inwardly extending upper and lower legs 19 and 20 respectively to provide a recess 21 into which the projecting

edge 16 of the shoe sole is received, Fig. 3. This clip may be fastened to the projection 16 in any manner desired, such as by providing semi-circular indentations along its edge, Fig. 3A, circular indentations 23 pressed inwardly from the body thereof, as shown in Fig. 3B, or rectangular indentations 24, as shown in Fig. 3C. However, there are many other ways of making these indentations, and they may be made of any shape desired and impressed in the metal at any part convenient.

In Fig. 4 the clip 17 is cut away at 25 at its top and bottom edges to provide the extending teeth 26. The teeth 26 may be pressed inwardly as indicated at 27, Fig. 5, for biting into the projecting edge of the sole for holding the clip securely to the shoe sole.

In practice, the clip 17 is inserted around the projecting edge of the sole and may extend completely around the sole as shown in Fig. 6, or it may be just placed along the edge of the sole where the wear is the greatest as shown in Fig. 1. After the clip is inserted over the protruding edge 16 of the sole, a device commonly known as a "rule", is procured for either making indentations into the metal for holding the clip to the sole as shown in Figs. 3A, 3B, and 3C, or for pressing the edges of the teeth into the sole, as shown in Fig. 5.

The normal position of an ice skate relative to the ice which is indicated generally as 28, is vertical as shown in full lines in Fig. 2. In making turns or in doing fancy or figure skating, the skater's body is at an angle relative to the ice and the skates will assume the position shown in dotted lines in Fig. 2. In this latter position the outer edge of the sole comes in direct contact with the ice, causing the sole to become worn, scuffed, or otherwise distorted. By applying the clip 17 to the projection 16 of the sole, as shown in Fig. 2, the clip will come in engagement with the ice and prevent the sole from being worn away. Should the clip become worn out after a considerable lapse of time, it may be removed and a new clip replaced. The shoe sole is thus kept from being worn away and always maintained in its normal rigid shape and position. The clip may be applied whenever it is most convenient to do so. It may be applied on the sole of the shoe and extend completely therearound before the shoe is made, or it may be applied to the sole of the shoe before the shoe is applied to the skate. The invention is also adaptable for application to the projecting edge of the sole after the shoe is completely made and a skate is fastened thereto. The sole engaging edge of the skate does not extend to the extreme edge of the sole as skates are usually made standard to fit various sizes of shoes. Then too, if the sole engaging portion of the skate extended flush with the edge of the sole, there

would be a relatively wide surface between the fastening means and the outer edge of the sole engaging portion of the skate. Ice, snow, and water would then be free to enter between the skate and the shoe sole and cause 70 the shoe sole to warp and become distorted. The clip is made substantially as wide or deep as the projecting edge of the shoe sole.

Instead of making the clips 17 from metal, they may be made of rubber or any other 75 suitable material which will stand up under use. When rubber is used, the clip is properly reinforced and fastened to the protruding sole edge in any manner desired. By lining the rubber clip with cloth, such as canvas, to reinforce the clip, a thoroughly practical clip is provided.

The invention provides a reinforcing member for a skate shoe which may be made of metal, rubber, or any other material which 85 answers the purpose. This member, regardless of the material from which it is made, prevents the edge of the shoe sole from coming in contact with the ice and thereby prevents the sole from being worn away. The 90 member is simple in construction, may be quickly and easily fastened to the protruding edge of the shoe sole, and may be readily and economically manufactured.

Changes may be made in the form, construction, and arrangement of the parts without departing from the spirit of the invention or sacrificing any of its advantages, and the right is hereby reserved to make all such changes as fairly fall within the scope of the 100 following claims.

The invention is hereby claimed as follows:

1. The combination of a shoe having a sole and a skate fastened to said sole, of a clip fastened to said sole about the outer edge 105 thereof for protecting that part of the sole which extends outwardly from the upper of the shoe, said clip being channel-shaped and having spaced legs between which the shoe sole extends, and indentations provided in 110 said clip for fastening it securely to a shoe sole.

2. A reinforcing metal clip for ice skate shoes comprising a channel-shaped member having spaced legs of substantially equal 115 length and providing a recess into which the shoe sole is received, and means for fastening said metal clip to the shoe sole at the upper and lower edges thereof.

3. A reinforcing metal clip for ice skate 120 shoes comprising a member having a recess into which the shoe sole is received, and parts pressed from the top and bottom of said clip and imbedded in the top and bottom respectively of the shoe sole for fastening the clip 125 securely to the sole.

In witness whereof, I have hereunto subscribed my name.
